UNITED STATES PATENT OFFICE.

PHILIP L. JOHNSON, OF WALLINGFORD, CONNECTICUT, ASSIGNOR TO R. WALLACE & SONS MFG. CO., OF WALLINGFORD, CONNECTICUT, A CORPORATION.

METHOD OF FORMING METAL PARTS FROM TUBING.

Application filed March 18, 1926. Serial No. 95,675.

Fig. 1 is a plan view of a part of hollow-ware formed in accordance with my method.

Fig. 2 is a side view, partly in section, of the same.

5 Fig. 3 is a perspective view of a ring cut from a piece of tubing.

Fig. 4 is a perspective view of a section of tubing from which the rings are cut.

Fig. 5 is a sectional view of a pair of dies 10 for forming the ring into a part shown in Figs. 1 and 2.

This invention relates to improvement in method of forming metal parts, such as feet, necks, bodies, bezels for covers, ornamental 15 "mount" wires, etc., as used in the manufacture of silver or silver-plated metal hollow-ware, or ring-shaped parts, either oval or round, for any other purpose. In the more general construction, these parts are formed 20 from sheet-metal, but, owing to the difficulty of forming the blank and operating the blank from thick stock, the cost is excessive. The object of this invention is to form these parts from sections of a metal tube, the 25 length of the sections and the thickness of the metal from which the tube is formed depending upon the article to be produced.

In carrying out my method, I cut a ring 10 from the end of a piece of metal tubing 30 11, the thickness of the tubing and the length of the ring cut off depending upon the article to be produced. This ring is then placed between suitable dies 12 and 13, and is struck to the desired shape,—for instance, that 35 shown in Figs. 1 and 2 of the drawings, wherein a foot 14 is shown.

The external diameter of the upper portion of the ring is reduced and the metal forced into the lower portion, which is thereby thickened and also expanded in diameter, 40 so that the rings are given the desired ornamental external configuration. These feet are used as bases for metal vessels.

With this method, the amount of material required for the finished article can be so 45 closely estimated that there is practically no flash after the pressing operation and, consequently, practically no waste of metal, as is the case in working up sheet-metal. The rings are readily produced by cutting a tube, 50 and avoids the cost of blanking-dies, which for heavy sheet-metal are expensive.

If the finished part is to be oval, the ring may be struck sidewise to form an oval ring 55 before the primary striking operation.

I claim:

A method of forming metal parts, consisting in cutting a tube of the desired thickness and diameter into rings and subjecting the rings to pressure between a pair of dies, 60 whereby the external diameter of the upper portion of the ring is reduced and the metal forced into the lower portion, which is thereby thickened and also expanded in diameter, 65 so that the said rings are given the desired ornamental external configuration.

In testimony whereof, I have signed this specification.

PHILIP L. JOHNSON.
